Primary Examiner — Susan Bennett Hattan(74) *Attorney, Agent, or Firm* — Fay Sharpe LLP(57) **CLAIM**

The ornamental design for an electronic circuit cabinet, as shown and described.

DESCRIPTION

FIG. 1 is a front perspective view of an electronic circuit cabinet showing our new design;

FIG. 2 is a front view of the electronic circuit cabinet of FIG. 1;

FIG. 3 is a rear view of the electronic circuit cabinet of FIG. 1;

FIG. 4 is a top view of the electronic circuit cabinet of FIG. 1;

FIG. 5 is bottom view of the electronic circuit cabinet of FIG. 1;

FIG. 6 is a left side view of the electronic circuit cabinet of FIG. 1; and,

FIG. 7 is a right side view of the electronic circuit cabinet of FIG. 1.
